UNITED STATES PATENT OFFICE.

BLAINE H. HARRIS, OF ST. PAUL, MINNESOTA, ASSIGNOR TO BROWN & BIGELOW, OF ST. PAUL, MINNESOTA, A CORPORATION OF MINNESOTA.

DESK CALENDAR.

Application filed February 18, 1926. Serial No. 39,164.

This invention relates to a desk calendar wherein it is desired to provide a desk utility having a particular use as a calendar to indicate the date and one which can be operated so that it will indicate each day separately and at the same time disclose and display an epigram.

The invention includes means associated with the days of the month, and made possible by using the back of the sheets indicating each day, for the epigrams. In this manner a condensed article is provided.

When made up in the desired manner it provides an attractive article of a desirable nature. It is obvious, however, that it may be used as a wall calendar when made in larger dimensions.

A feature of the invention resides in providing a small proportioned article to indicate in a large, prominent figure the day of the month, also means for indicating the particular day and the month of the year.

My invention includes means for enclosing sheets of the calendar supported in a manner so that the back of the same is displayed through an opening in a hinged frame which conceals the sheets before they are turned down in position to indicate the particular day of the month. This is an important feature of my invention.

The invention also includes means for providing a supporting easel arm which is removable and which can be made to lie flat against the back when the calendar is shipped or packed away.

These features, together with other objects and details of construction will be more fully and extensively set forth in the specification and claims.

In the drawings forming part of this specification:

Figure 1 is a perspective view of my calendar.

Figure 2 is a similar view illustrating the sheet enclosing frame elevated and the operation of the sheets as they are dropped from the enclosing frame.

Figure 3 is a central sectional elevation of my calendar.

Figure 4 is a back view of the same.

Figure 5 is a perspective of a detail of my calendar.

In the drawings my calendar A is designed to provide a utility for displaying the day of the month, the particular day and the

particular month, together with means for framing and enclosing the sheets of the calendar so that the back of the sheet is displayed.

The body of the calendar 10 is made of sheet material such as metal or other suitable material of a stiff nature so as to provide an upright back portion. On the body 10 I provide a pair of loops 11 which are riveted at 12 to the back 10. The other end of the loops 11 are formed with a hook 13 which engages through the back. The loops 11 are formed of an angular nature having a flat portion 14 which extends approximately parallel to the back 10 and side portions 15 which extend approximately at right angles to the portion 14.

The particular shape of the loops 11 with the angularly disposed sides provide means for holding the daily sheets 16 which make up the days of the month of the calendar A. The sheets 16 are formed with rectangular openings 17 through which the loops 11 engage so as to hold the sheet 16 in position on the back 10 of the calendar A.

The front face 18 of each of the sheets 16 is provided with a numeral such as 19 to indicate the particular day of the month. The back face 20 of each sheet 16 has printed thereon an epigram or other display material which is adapted to cooperate with the face of the preceding numeral to form a display face.

When the sheets 16 are in depending position from the lower side 15 of the loop 11 the face 18 indicates the day of the month. The remaining sheets 16 are held on the upper portion 15 of the loop 11 and are adapted to be covered by the hinged cover member B. This member is pivotally secured at 21 to a pair of ears 22 which are struck up from the back portion 10 as indicated in the back view in Figure 4, and as also illustrated in the sectional view in Figure 3. The ears 22 hold the cover B in position to conceal the sheets 16 on the upper portion 15 of the loops 11 and the cover B is formed with a depending portion 23 which covers the upper portion of the sheets 16 hinged on the lower portion 15 of the loop 11 and also conceal the loops 11 when the cover is in downward position. The cover B is formed with side flanges 24 which depend from either side of the same and which are adapted to form stops engaging against the face of the back 110

10. In this manner a rectangular compartment is formed by the cover B and the back 10 in which the sheets 16 are concealed when they are held in upper position on the back 10.

10 An opening 25 is formed in the cover B through which the back surface 20 of the sheets 16 is clearly visible and by this opening or window in the cover B I provide a means for displaying the back of each of the card sheets 16 so that the epigrams 26, or other suitable display on the back faces 20, is clearly visible at the time the face 18 of each of the sheets is visible directly below the 15 cover B and held depending from the loops 11. The lower portion of the cover B is free to be lifted as illustrated in Figure 2 so that the sheets 16 may be turned on the loops 11 and permitted to depend into the position 20 illustrated to indicate the day of the month.

Ordinarily, my calendar A is provided with a supporting leg 27 which is removably attached to the loop 28 formed in the back 10 and provided with a detent 29 which is 25 adapted to engage in the recess 30 formed in the tongue 31 of the leg 27 so as to lock the tongue 31 under the loop 28. A foot portion 32 is formed on the end of the leg 27 opposite to the tongue 31.

30 The back 10 is provided with openings 35 and 36 which are adapted to be positioned on either side of the display position of the cards 16 when in position to indicate the day of the month. The opening 35 is adapted to 35 expose a portion of a disk 37, while the opening 36 exposes a portion of the disk 38. The disks 37 and 38 are pivotally secured to the back 10 with a portion of each disk overlapping at the center and the outer edges of each disk being exposed at 40 to provide a hand engaging edge so that the disks can be rotated. The opening 35 is adapted to expose the days of the week individually, the disk 37 having printed thereon each day of 45 the week so that as the disk is rotated it exposes the day through the opening 35. In the same manner the disk 38 is adapted to disclose the month of the year through the opening 36.

50 In this manner I provide a calendar having features of a desirable nature, permitting sheets of the calendar to have a dual function and protecting the sheets by means which virtually forms a frame adapted to 55 cover the edges of the sheets and the sheet holding means so that when the calendar

is in use it has a neat, attractive appearance. The construction is simple and the calendar can be set up on a desk or it may be hung up on the wall. When used as a desk utility 60 it may be made of such dimensions as to have a convenient size, yet permit a very large numeral to indicate the day of the month. The epigrams associated with each 65 day are constant reminders to the individual using the calendar, and stimulate the appeal of the calendar to customers.

In accordance with the patent statutes, I have described the principles of operation 70 of my calendar, together with the best embodiment thereof, and while I have illustrated a particular construction and formation of the same in the drawings I desire to have it understood that the same are only suggestive of a means for carrying out my 75 invention and that the same can be applied to uses other than those above set forth, within the scope of the following claims.

I claim:

1. A calendar having a back formed of 80 sheet material, a pair of ears struck up from said back, a cover hingedly supported by said ears having three sides extending therefrom and having an opening formed in one of said sides, a series of cards adapted to indicate the days of the month supported beneath said cover in a manner so as to extend from the open side of said cover or to be enclosed beneath said cover to conceal the same and a removable supporting bracket 85 for said calendar.

2. A calendar, a back, a removable bracket member, a frame cover, a series of sheets adapted to indicate the days of the month concealed beneath said cover before they 95 are desired for use, an opening in said frame to permit said sheets to depend from said cover to indicate the day of the month, indicating disks and openings in said back adapted to indicate the day of the week and 100 the month of the year from said disks.

3. A calendar including a series of card sheets adapted to indicate the days of the month, a cover frame hingedly supported in a manner to conceal the sheets before they 105 are desired for use, an opening formed in said cover to expose the back of the sheets and supporting means for said sheets concealed beneath said cover and adapted to permit the sheets to depend from the open side 110 of said cover when in use.

BLAINE H. HARRIS.
